UNITED STATES PATENT OFFICE.

CHARLES CARTER MONTAGUE, OF AUGUSTA, ARKANSAS.

AUTOMATIC REGISTERING-STAMP.

SPECIFICATION forming part of Letters Patent No. 319,003, dated June 2, 1885.

Application filed November 28, 1884. (No model.)

To all whom it may concern:

Be it known that I, CHARLES C. MONTAGUE, a citizen of the United States, residing at Augusta, in the county of Woodruff and State of Arkansas, have invented certain new and useful Improvements in Automatic Registering-Stamp; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to automatic registering-stamps; and it consists in a registering device which may be attached to a dotting, canceling, or numbering stamp, but is more particularly designed for a post-office canceling-stamp.

20 Figure 1 is a face view of my registering device A, attached to a post-office canceling-stamp. Fig. 2 is a rear view of the same attached to the same stamp. Fig. 3 is a view with the face-plate and numbering-dials removed, showing the operating mechanism. Fig. 4 is a view of operating foot and plate. Fig. 5 is an edge view of the operating-wheels. Figs. 6 and 7 are detail views.

25 My invention is described as follows:

Between two plates, A' B, which are secured together by the usual posts at the four corners, are the operating-wheels of the dials 1 2 3, operating-wheels 4 5 6, operating-plate 7, together with the springs and levers.

30 The ratchet-wheel 4 operates all the other wheels. As it moves round, finger a comes in contact with the cogs on wheel 5, and moves it the distance of one cog round. Wheel 5 being rigidly fastened to the same shaft with dial 2, it moves the said dial 2 one notch round. This dial 2 has on its lower face a finger, b, which comes in contact with the cogs on wheel 6, and moves the same one cog round, and also dial 3 one notch round, as it is rigidly secured on the same shaft with wheel 6.

35 The plate 7 is secured in place by headed pins c c, working through slots c' c', which allows the said plate to move up and down. The said plate 7 is held down by the combined action of the springs e e', and it is forced up by foot 8 when the stamp is struck down on the

letter or other thing to be stamped. The lower end of the foot 8 is hollow, in which is inserted a piece of india-rubber, f, the object of which is obvious. This plate 7 has pivoted to its face a pawl, d, which comes in contact with the teeth of wheel 4, and is held down to its work by a spring, d'. When the plate 7 moves up, the pawl d moves the wheel 4 round one notch, and when it has completed its work a pin, d'', drops into another notch and prevents the wheel from moving round any farther, and at the same time spring d' drops into another notch, so that said ratchet-wheel will not be moved back by friction on the pawl d when it moves down.

40 When the finger a moves the wheel 5 round, said wheel is held in place by the pawl g, which is thrown in between the teeth by means of the spiral spring g'; and when the wheel 6 is moved round one notch by finger b, said wheel 6 is held in place by pawl g'', which is thrown in between the teeth of said wheel by means of said spring g''. This spiral spring g' is coiled round the post g'' and operates both of the pawls g and g''.

45 Every time the plate 7 is thrown up it comes in contact with the long arm of the lever h, and throws the pin h' into one of the notches in the periphery of the dial 3, which, in combination with pawl g'', keeps it from moving round until operated by finger b.

The indicator, when completed, is secured to the stamp C by a strap, D, which passes round the lower part of the handle of said stamp, the ends of which strap are bound to the plate B by means of two other straps, E E, which pass over the ends of said strap D, thence through perforations F in the plate B, and are headed on the under side of said plate.

50 When my invention is thus completed, two strokes (one to ink the stamp and one to stamp the envelope) move the dial-plate 1 from 0 to 1. Two more strokes move it to 2, and so on in the usual manner.

Having thus described my invention, what I claim as new, and desire to secure by Letters Patent, is—

55 1. In a registering device, as above described, the combination of plate 7, having hollow foot 8 and rubber cushion f, slots c' c', working on pins c c, spring d', and pawl d, pivoted to said plate and operating wheel 4, pin d'', secured in

said plate and checking said wheel 4, and springs *e* and *e'*, returning said plate to position, substantially as shown and described.

2. In a registering device, as described, the combination of plate 7, having foot 8, rubber cushion *f*, with springs *e* and *e'*, lever *h*, pin *h'*, and dial-plate 3, substantially as shown and described.

3. The combination of the registering device 10 A with stamp C, said device being bound to the lower end of the handle of said stamp by

the strap D and the straps E E, in the manner described, with its foot 8 extending below the lower end of said stamp, for the purposes described.

In testimony whereof I affix my signature in presence of two witnesses.

CHARLES CARTER MONTAGUE.
